BOBBIN STRIPPER

Edgar A. Terrell, Charlotte, N. C., assignor to The
Terrell Machine Company, Charlotte, N. C., a
corporation of North Carolina

Application January 24, 1931, Serial No. 511,022

26 Claims. (Cl. 28—20)

The invention relates to bobbin strippers, and especially to machines of the general character shown in my Patent No. 1,740,128, dated December 17, 1929.

5 The general object of the invention is to provide, in a machine of the stated type, or of similar organization or mode of operation, wipers, brushes or equivalent means for removing from the bobbin-barrels trailing threads, fragments of 10 waste, or lint remaining thereon after a stripping action in which blades cooperate with the barrel and the waste yarn thereon to remove the bulk of such waste; and means for operating such wipers or the like in proper relation to other parts of 15 the machine, especially the bobbin-advancing means, and the bobbin moved thereby.

Another object is to so arrange or organize the wiping mechanism or analogous waste residue removing means, that it may easily and quickly 20 be applied as an attachment to a stripping machine of the general character referred to, and will then operate in proper coordination with other parts of the machine.

The characteristics and advantages of the invention are further sufficiently explained in connection with the following detail description of 25 the accompanying drawings, which show one preferred embodiment. After considering this example, skilled persons will understand that many 30 variations may be made without departing from the principles disclosed; and I contemplate employment of any structures that are properly within the scope of the appended claims.

Having reference to the drawings,—

35 Fig. 1 is a top plan of a stripping machine embodying the invention in one form, parts of the machine proper which are not essential to an understanding of the invention being omitted.

Fig. 2 is a central, vertical, longitudinal section, 40 enlarged.

Fig. 3 is a transverse section at 3—3, Figs. 1 and 2.

The invention structure is, in the present embodiment, incorporated in or applied to a stripping machine of the type disclosed in my patent referred to above, including, as also here shown, a main frame or bed having longitudinal side-members or rails 1, stripper-blade assemblies 4 oppositely located on the side rails, a push-head 5 mounted for reciprocation in guides on the side rails and having a tip-socket 10 and a pushing face 13 to engage the bobbin tip-end, and a pull-head 16, also reciprocating in guides in the side rails, and having jaws 19 to grasp the bobbin-barrel just behind the head. The waste-carry-

ing bobbins are advanced to an initial stripping position by a feed-chute, as fully shown in the patent referred to, and here omitted. In this position the bobbin-head rests on supports 22 provided in the guide-blocks 25 of the stripping-assemblies 4, with the inward face of the head, or the fillet connecting such face to the feeler-barrel, adjacent the thin stripper-blades 28, and also adjacent downwardly-convergent positioning edges 31 of the guide-blocks (or on tongues of 10 cover-plates 34 adjustable thereon, as disclosed in my companion application filed Aug. 22, 1931, Serial No. 563,137). The guide-blocks also usually support other stripping blades 37.

The pull-head 16 is reciprocated by a pitman 15 40, connected to a crank 43 on a shaft 46, which is mounted in bearings 49 on frame-members 1 near the rear (delivery) end of the machine. The shaft is driven by a bevel gear 52 fixed on one of its ends, and a pinion 55 engaging the gear, 20 and carried by a longitudinal driving shaft 58.

The novel and improved bobbin-barrel wiping mechanism, adapted as an attachment for, or combined with essential features of a bobbin-stripper as above described, is constructed and 25 arranged as follows:

Wiper-supports or arms 61 are mounted between the forward faces of the stripper-blade guide-blocks and the pull-head and at opposite sides of the axis of bobbin-movement, for movement toward and from such axis. At the upper end of each arm is a wiper 64, which in the form shown is a brush; and preferably these 30 wipers are detachably mounted on the arms, to facilitate repair or replacement. For this purpose each wiper consists of a head or body 67 detachably secured to the arm end as by screws 70, with bristles or teeth 73 which may be of wire or other material, set in the body-face which is directed toward the other wiper. Instead of wires or bristles the active wiping elements may be of card-clothing, or strips of suitable flexible material such as felt or leather, of substantial thickness, adapted to engage the bobbin-barrel with the necessary firmness, but without injury thereto, and to wipe or clean off any residual waste, trailing threads or lint remaining after the action of the stripping blades, as the bobbin is advanced lengthwise, first by the push-head and then by the jaws of the pull-head. The arms or equivalent wiper-supports are operated by connection with a driving element of the machine, in timed relation to movements of the push- and pull-heads, and of the 40 bobbin, being moved divergently prior to the 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 first advancing movement of the bobbin, to allow passage of the head without engagement with the wipers, and are then moved convergently, to bring the active wiping elements into engagement with the barrel adjacent the head, and are retained in this position until the bobbin-tip passes away from between them, so that the residual waste is effectively removed from the barrel.

10 The mode of mounting and operating the wiper arms or equivalent elements may vary considerably. As here shown, the arms have an oscillating movement and for this purpose they are carried by the forward ends of rockshafts 16 and 77. Each arm has a sleeve or hub-portion 79 receiving the shaft-end, and detachably secured to it, as by set-screws 82. Each shaft is mounted for oscillation in bearings 85 at the ends of a shaft-support or frame-piece 88 which is arranged for connection to the under face of one of the machine-frame side-members 1, as by bolts 91 passing through registering holes in the respective frame-members. The rockshafts are connected to move simultaneously by arms 94 secured on them between the bearings 85. These arms extend inward and slightly downward, below the path of movement of pull-head 16, and their ends are connected as by a pin or screw-stud 97 set in one of them and engaging in a slot 100 in the other.

One of the rockshafts, 77, has at its rear end an arm 103 including a portion extending downward and thence curving outward and rearward, as is necessitated by the machine frame, and another portion projecting upward, and provided with a cam-roller 106 to cooperate with a cam 109, which is operatively connected with a shaft 46 above referred to, which drives pull-head 16. This cam has a semi-circumferential concentric portion 112, an eccentric gradual-rise portion 115 leading to a concentric dwell portion 118, and a nearly-radial quick-drop portion 121. It also has a central circular aperture 124 to fit about the hub 121 of gear 52, and an arcuate slot 130 through which passes a screw 133 engaging in a tapped hole in the gear. This screw-and-slot connection provides for securing the cam to rotate with the gear and shaft, and also for relative angular adjustment of the cam, to properly time the wiper action in relation to movements of the pull-head and bobbin. The cam may also have a lug 136 through which passes a set-screw 138 engaging with the gear hub to aid in securing the cam to the gear.

55 Cam-follower arm 103 above mentioned, has a lug 142 tapped to receive a stop-screw 145 which is secured in adjusted position by a lock-nut 148. The head of this stop-screw engages an under face of one of the main frame side-members 1, and is normally held in this position by a spring 151, tensioned between a stud or screw 154 set in arm 103 and the end of a screw 157, which passes through a hole in a bracket 160 secured as by a screw 163 to the top face 60 of a frame side-member 1. Screw 157 is secured to the bracket by nuts 166, and by obvious manipulation of these nuts may be moved axially therein to adjust the tension of spring 151. The spring acts as a motor element to rotate rock-shaft 77 and the other shaft 16 connected thereto by arms 94, in directions to cause the wipers 64 to move convergently to an extent limited by stop-screw 145, which is adjusted with reference to the bobbin-barrel diameter and the degree of pressure to be exerted by the wiping ele-

ments, such as wires or bristles 13, upon the bobbin-barrel. The engagement of the wipers with the bobbin-barrels is thus effected by and dependent upon spring-pressure, avoiding greater complications in structure or adjustment which would be involved in positive convergent movement of the wipers, and also avoiding excessive pressure and consequent scratching or scoring of the barrels, where toothed elements are used.

10 When the wipers are in active or wiping position as just described, stop-screw 145, as clearly shown in Fig. 2, also holds the cam roll 106 considerably away from the smaller concentric portion 112 of cam 109. This normal clearance permits the wipers to move convergently to the desired extent, as limited by engagement of the stop-screw with the frame, and also permits an ample range of adjustment by the screw to allow the wipers to come closer together as the bristles wear.

15 With the parts in the positions shown, crank 43 and pitman 40 are at rear dead-center, corresponding to the rearmost position of pull-head 16, whose jaws 19 have opened to release a bobbin, the barrel of which has in the preceding rearward movement of the jaws been drawn between the wipers 64, which were and still are maintained in their inward or wiping positions by spring 151, the convergent movement of the wipers being limited, as above explained, by stop-screw 145. In 20 the continued rotation of shaft 46 in the direction of the arrow (Fig. 2), the pull-head 16 is moved forward to receive another bobbin, and in the first part of this movement the eccentric face 115 of cam 109 strikes roll 106 and causes the wipers to move divergently sufficiently to permit free passage between them of a bobbin-head of largest diameter. When the larger concentric or dwell portion 118 of the cam engages the roll, the wipers are separated to the maximum extent, and are so held open until the pull-head has nearly completed its forward stroke. At this time the push-head has advanced the bobbin initially between the stripping blades which grasp and push the mass of waste relatively rearwardly on the bobbin-barrel until the inward face of the head has passed the wipers; the quick-drop portion 121 of the cam has now reached cam roll 106 and spring 151 acts to turn the rockshafts and move the wipers convergently to engage the barrel. At about this time the pull-jaws converge to engage about the barrel at the inward face of the head, and the bobbin is pulled through between the wipers and any residual waste is removed from the barrel, as 25 above sufficiently explained.

30 It will now be understood that the invention structure may be considered as being embodied in a complete stripping machine of the general character described; or that otherwise it may be understood to consist in wiping mechanism capable of quick and easy attachment to such a machine. When designed as an attachment, the machine as designed and built may have provision for placing the wiper mechanism thereon without machining operations and by the use of ordinary tools such as a wrench and screw driver; thus, the machine frame-side-members may have holes drilled therein in proper positions to receive the bolts 91 for securing the rockshaft frame pieces; and these bolts may in fact be used in absence of the wiper attachment to hold in place the retaining plates or gibs 169 of the pull-head guideways 175 and will also serve the same purpose after the rockshaft frame pieces 88 are attached. One of the frame side-members may also be drilled and 35

tapped to receive the retaining screw 163 for bracket 160, and gear 52 may be drilled and tapped to receive the cam-securing and adjusting screw 133. No other provision or modification need be made in the machine proper for reception of the wiping mechanism, which does not interfere with any of the parts or functions of the complete machine.

What I claim is:

- 10 1. In a bobbin-stripper, the combination with stripping means engaging the bobbin, a push-head, and a pull-head, of opposed brushes presenting a discontinuous surface of fiber-engaging pointed teeth clasping the bobbin, to wipe off residual waste remaining after the action of the stripping blades.
- 15 2. In a bobbin-stripper, the combination with stripping means engaging the bobbin, a push-head, and a pull-head, of opposed brushes presenting a discontinuous surface of fiber-engaging pointed teeth yieldingly urged to clasp the bobbin, to wipe off residual waste remaining after the action of the stripping blades.
- 20 3. A bobbin-stripper having in combination stripping devices, means for producing relative movement between such devices and a bobbin to effect the stripping, brushes clothed with sharp points adapted to clasp the bobbin to remove residual waste, and means for spreading the 25 brushes to permit passage of the bobbin-head therebetween while the stripping devices are working.
- 25 4. In a bobbin-stripper, the combination with stripping means, a pusher for advancing a bobbin lengthwise in relation to the stripping means in a stripping action, and a puller for completing bobbin advance, of means structurally independent of the stripping means for wiping residual waste from the bobbin barrel during the bobbin's 30 advance, and means for advancing and retracting said wiping means in relation to the barrel.
- 30 5. A bobbin-stripper comprising in combination, stripping means, a puller for advancing a bobbin lengthwise, driving means for moving the 35 puller to and fro, and means beyond the stripping means in the direction of bobbin movement for wiping residual waste from the bobbin barrel, independently actuated by said driving means to advance and retract the wiping means in relation to the bobbin barrel.
- 35 6. In a bobbin-stripper, the combination with stripping means, means engaging the bobbin surface for positioning a bobbin for action of the stripping means, and means for advancing the 40 bobbin longitudinally in a stripping action, of wipers mounted for movement in a plane perpendicular to the bobbin axis toward and from the bobbin barrel at opposite sides thereof beyond the stripping means, and means for operating the wipers independently of the stripping means.
- 45 7. A bobbin-stripper comprising in combination, stripping means, means for positioning a bobbin for action of the stripping means, and means for advancing the bobbin longitudinally in a stripping action, wipers mounted for movement toward and from the bobbin barrel at opposite sides thereof, means connecting the wipers for concurrent movement, and wiper-operating 50 means acting after the stripping means.
- 50 8. A bobbin-stripper comprising in combination, stripping means, means for positioning a bobbin for action of the stripping means, and means for advancing a bobbin longitudinally in a stripping action, wipers mounted for movement 55

toward and from the bobbin barrel at opposite sides thereof, means connecting the wipers for concurrent movement, and means for retracting the wipers prior to a stripping action and for advancing them to engage the barrel after the stripping means have engaged the bobbin-barrel.

9. A bobbin-stripper comprising in combination, stripping means, means for positioning a bobbin for action of the stripping means, a pusher for advancing the bobbin lengthwise and a puller 10 for completing such bobbin advance, a shaft connected to reciprocate the bobbin-puller, wiping elements at opposite sides of the path of bobbin movement posterior to the stripping means, means supporting the wipers for movement toward and from the bobbin, a cam on said shaft, and means operated by the cam for moving the wiping elements convergently and divergently.

10. In a bobbin-stripping machine, in combination, a stationary frame providing guides for 20 a push-head and a pull-head which move convergently and divergently, stripping blades and bobbin locating means on the frame intermediate the push-head and pull-head, a driving shaft connected to reciprocate the pull-head, wiper-supports mounted on the frame for movement toward and from a bobbin advanced between the stripping blades by the push-head and pull-head, wiping elements on said supports to cooperate with the bobbin barrel and remove residual waste therefrom, and means actuated by said shaft for moving the wiper-supports.

11. In a bobbin-stripping machine, in combination, a pull-head, stripping blades, a driving shaft connected to reciprocate the pull-head, 35 rockshafts, wiper arms carried by the rockshafts adjacent the stripping blades, wiping elements on the arms to engage the bobbin barrel and remove residual waste therefrom, means connecting the rockshafts to move together, a cam on said driving shaft, and an arm on one of the rockshafts having a follower cooperating with the cam.

12. In a bobbin-stripping machine, in combination, a pull-head, stripping blades, a driving shaft 45 connected to reciprocate the pull-head, rockshafts mounted for oscillation at opposite sides of the path of bobbin movement, wiper arms carried by the rockshafts adjacent and posterior to the stripping blades, wiping elements on the arms 50 to engage opposite sides of the bobbin barrel and remove residual waste therefrom, means connecting the rockshafts to move together, a cam adjustably mounted on said shaft, and an arm on one of the rockshafts having a follower 55 cooperating with the cam.

13. Wiper mechanism organized as an attachment for a bobbin-stripping machine of the general character described, and employing stripping blades, said mechanism comprising supports 60 adapted for attachment to the machine frame, wiping elements movably mounted on the supports and adapted to cooperate with a bobbin barrel, and wiper-operating means structurally independent of the stripping blades adapted for cooperation with a driving element of the machine.

14. Wiper mechanism organized as an attachment for a bobbin-stripping machine of the general character described, and employing stripping blades said mechanism comprising supports 70 adapted for attachment to the machine frame, wiping elements movably mounted on the supports and adapted to cooperate with a bobbin barrel, wiper-operating means structurally inde- 75

- pendent of the stripping blades adapted for co-operation with a driving element of the machine, and an adjustable stop arranged to cooperate with a fixed part of said machine to limit 5 movement of said wiping elements.

15. Wiper mechanism organized as an attachment for a bobbin-stripper of the general character described, said mechanism comprising rockshafts, supports in which the rockshafts are 10 mounted for oscillation and adapted for attachment to the stripper frame, wiper arms on the shafts and wiping elements carried by the arms to cooperate with a bobbin barrel, and another arm on one of the shafts having a cam follower 15 for cooperation with a cam to operate the rockshaft.

16. A bobbin-stripper having in combination stripping devices, means for producing relative movement between such devices and a bobbin 20 to effect the stripping, a wiper yieldingly actuated into engagement with the bobbin subsequent to the stripping devices, a rotary member, means engaging with such member to move the wiper away from the bobbin, and means apart from the 25 member for limiting the movement of the wiper toward the bobbin.

17. A bobbin-stripper comprising in combination, stripping means, means for positioning a bobbin for action of the stripping means, a pusher 30 for advancing the bobbin lengthwise and a puller for completing such bobbin advance, means for driving the puller, wiper elements independent of the stripping means mounted at opposite sides of the path of bobbin movement posterior to the stripping means, and means operated by the puller driving means to move the 35 wiping elements divergently permitting passage of the bobbin-head and convergently to engage the barrel and wipe residual waste therefrom.

18. A bobbin-stripper having in combination 40 stripping means, means for positioning a bobbin for action of the stripping means, a pusher for advancing the bobbin lengthwise and a puller for completing such bobbin advance, a shaft connected to reciprocate the bobbin puller, a cam on 45 the shaft, parallel rockshafts mounted for oscillation at opposite sides of the axis of movement of the pusher and puller, arms on the shafts, wiping elements carried by the arms for cooperation 50 with opposite sides of the bobbin barrel adjacent and posterior to the stripping means, means connecting the rockshafts to move simultaneously, and an arm on one of the shafts having a follower cooperating with the cam.

19. In a bobbin-stripping machine, in combination, a stationary frame providing guides for 55 a push-head and a pull-head which move convergently and divergently, stripping blades and bobbin locating means on the frame intermediate the push-head and pull-head, a driving shaft connected to reciprocate the pull-head, wiper-supports mounted on the frame for movement toward and from a bobbin advanced between the 60 stripping blades by the push-head and pull-head, wiping elements on said supports to cooperate with the bobbin barrel and remove residual waste therefrom, a spring arranged to move the wiper-supports convergently, and means actuated by said shaft for moving said supports divergently.

20. In a bobbin-stripping machine, in combination, a pull-head, stripping blades, a driving shaft connected to reciprocate the pull-head, rockshafts, wiper arms carried by the rockshafts 65 adjacent the stripping blades, wiping elements 70 adjacent the stripping blades, wiping elements 75

on the arms to engage the bobbin barrel and remove residual waste therefrom, means connecting the rockshafts to move together, a cam on said driving shaft, an arm on one of the rockshafts having a follower cooperating with the cam, and a spring acting on one of the rockshafts to move the wiper arms convergently.

21. In a bobbin-stripping machine, in combination, a pull-head, stripping blades, a driving shaft connected to reciprocate the pull-head, 10 rockshafts, wiper arms carried by the rockshafts adjacent the stripping blades, wiping elements on the arms to engage the bobbin barrel and remove residual waste therefrom, means connecting the rockshafts to move together, a cam on 15 said driving shaft, an arm on one of the rockshafts having a follower cooperating with the cam, a spring acting on one of the rockshafts to move the wiper arms convergently, and a stop limiting such convergent movement.

22. In a bobbin-stripping machine, in combination, a pull-head, stripping blades, a driving shaft connected to reciprocate the pull-head, 20 rockshafts, wiper arms carried by the rockshafts adjacent the stripping blades, wiping elements on the arms to engage the bobbin barrel and remove residual waste therefrom, means connecting the rockshafts to move together, a cam on said driving shaft, an arm on one of the rockshafts having a follower cooperating with the cam, a spring acting on one of the rockshafts to move the wiper arms convergently, and a stop limiting such convergent movement.

23. Wiper mechanism organized as an attachment for a bobbin-stripper to the general character described, said mechanism comprising 30 rockshafts, supports in which the rockshafts are mounted for oscillation and adapted for attachment to the stripper frame, wiper arms on the shafts and wiping elements carried by the arms to cooperate with a bobbin barrel, another arm 35 on one of the shafts provided with a cam follower, and a cam adapted for adjustable connection to a rotary driving element of said machine and to cooperate with the cam follower to determine convergent movement of the wiper arms independently of the cam.

24. Wiper mechanism organized as an attachment for a bobbin-stripper of the general character described, said mechanism comprising rockshafts, supports in which the rockshafts are 40 mounted for oscillation and adapted for attachment to the stripper frame, wiper arms on the shafts and wiping elements carried by the arms to cooperate with a bobbin barrel, another arm 45 on one of the shafts having a cam follower for cooperation with a cam to operate the rockshaft, and a spring connected to said follower arm, the spring being adapted for connection also to a fixed point of the machine frame and yieldably acting to move said wiper arms convergently.

25. Wiper mechanism organized as an attachment for a bobbin-stripper of the general character described, said mechanism comprising rockshafts, supports in which the rockshafts are 50 mounted for oscillation and adapted for attachment to the stripper frame, wiper arms on the shafts and wiping elements carried by the arms to cooperate with a bobbin barrel, other arms 55 on the shafts and a connection between such arms to cause the rockshafts to move simultaneously.

neously, a rotating cam, and cam-following means on one of the shafts for cooperation with the cam to operate the rockshaft.

26. Wiper mechanism organized as an attachment for a bobbin-stripper of the general character described, said mechanism comprising rockshafts, supports in which the rockshafts are mounted for oscillation and adapted for attachment to the stripper frame, wiper arms on the

5 to cooperate with a bobbin barrel, a connection between the rockshaft to cause them to move simultaneously, another arm on one of the shafts having a cam follower for cooperation with a cam to operate the rockshaft, and a spring connected to said follower arm, the spring being adapted for connection also to a fixed point of the machine frame and yieldingly acting to move said wiper arms convergently.

EDGAR A. TERRELL. 10

CERTIFICATE OF CORRECTION

Patent No. 2,009,709.

July 30, 1935.

EDGAR A. TERRELL.

It is hereby certified that error appears in the printed specification of the above numbered patent requiring correction as follows: Page 3, first column, lines 52 and 53, claim 6, after "means" second occurrence, strike out the words "engaging the bobbin surface" and insert the same after "means" first occurrence and before the comma, in same line and claim; and that the said Letters Patent should be read with this correction therein that the same may conform to the record of the case in the Patent Office.

Signed and sealed this 17th day of September, A. D. 1935.

Leslie Frazer

(Seal)

Acting Commissioner of Patents.
